UNITED STATES PATENT OFFICE.

ELBRIDGE G. DYER, OF HAMILTON, OHIO, ASSIGNOR TO OWENS, LANE,
DYER & CO., OF SAME PLACE.

IMPROVEMENT IN THRASHING-MACHINES.

Specification forming part of Letters Patent No. 35,648, dated June 17, 1862.

To all whom it may concern:

Be it known that I, ELBRIDGE G. DYER, of Hamilton, Butler county, Ohio, have invented a new and useful Improvement in Grain Thrashing and Separating Machines; and I do hereby declare the following to be a full, clear, and exact description thereof, reference being had to the annexed drawing, making part of this specification.

My invention relates to the provision of an auxiliary cleaning attachment at the discharging portion of a grain thrasher and separator.

In the use of the customary separating appliances of a thrashing-machine there often occur conditions of grain from which the ordinary shoe is inadequate to discharge all the lighter refuse without at the same time blowing over and wasting much of the good grain, and hence a large portion of machine-thrashed grain has to undergo a second winnowing in the mill before grinding, an expensive and troublesome operation, which would be wholly unnecessary if a complete cleaning could be effected in the first instance.

The object of the present improvement is to provide an auxiliary winnowing attachment applicable to any thrashing-machine, which attachment may be momentarily available at the option of the operator, and in any degree that the condition or character of the particular grain being operated upon may render necessary, so as to insure the delivery of a perfectly "malleable" article with every description of grain.

The drawing is a perspective view of a thrashing-machine provided with a winnowing attachment having its outer wall removed for the purpose of illustration.

A represents the rear portion of a thrashing and separating machine.

B is the fan, (the journal-bearing being omitted.)

C is one of two similar fan-mouths.

D is the grain-delivering spout.

E is a suction wind tube or spout, which may have a form approximating to that of an inverted U. The receiving-limb e of the spout E is open at bottom to allow the good cleaned grains (see red arrow 1) to drop below into a sack or other receptacle. The discharging-limb e' opens into a draft-chamber, F, from which (when the attachment is employed) the fan is compelled to draw its supply of wind.

In order that all the chess, cheat, and other heavier portions of the light refuse may be caught in the limb e', the wind-passage is enlarged as it approaches the elbow e", and undergoes still further enlargement at the chamber F, resulting in a lull and eddy at this point which leaves the said heavier refuse (see blue arrow 2) to be projected by its momentum into the lower portion of the limb e', while the dust, chaff, white caps, and all other very light matters escape into the fan and are discharged at the shoe-tail. (See black arrow 3.) The light grains and seeds detained in the limb e' are removed, when convenient, by means of a door, G, and are useful for chicken or hog feed.

A registered opening (see red lines H) in the outer wall of the draft-chamber, opposite the fan-mouth, enables the operator to graduate with the greatest nicety the action of the winnowing-spout by permitting a greater or less amount of direct draft into the fan. The opposite mouth of the fan is guarded by similar registers. I find by practical test that the fan-mouth O next the draft-chamber F is required to exceed that on the other side by about an eighth of the latter's diameter.

A register, I, within the tube affords an additional means of regulating the auxiliary winnowing, and also enables the entire closing of the tube when no auxiliary action is required.

When a large quantity of grain not needing auxiliary winnowing is to be operated on, the spout E may be unshipped by disengaging the hooks J. It is found that the wind in the spout E acts separately on each individual grain to a degree which is impracticable within the limits of the shoe without blowing away grain and refuse together.

I claim herein as new and of my invention—

The application to the grain-delivery of a thrashing-machine of the winnowing suction-spout E, in combination with the shoe-fan, the whole being constructed, adapted, and regulated, substantially as set forth.

In testimony of which invention I hereunto set my hand.

ELBRIDGE G. DYER.
